SEALING MEANS FOR DOOR BOTTOMS

Ralph E. Uphoff, Madison, Wis.

Application March 25, 1949, Serial No. 83,377

14 Claims. (Cl. 20—69)

1

My invention relates, generally, to weather-stripping and it has particular relation to sealing means for door bottoms.

Fire ordinances or codes in most municipalities require that entrance doors in commercial buildings swing outwardly. Such ordinances usually relate to hotels, restaurants, retail stores of all kinds, apartment buildings, office buildings, factories, garages, and other buildings open to the public. It is well known that these entrance doors are exposed to the weather and that, when made of wood, are subject to swelling and shrinking as changes take place in the relative humidity and they are subjected to snow, hail, sleet, rain, sunshine, etc.

It is well known, of course, that doors of the type which hinge or swing along one upright edge close against a stop or jamb. The stop or jamb overlaps the door and cuts out drafts on the top and sides without requiring that the door be fitted too tightly in the door frame. With a properly fitted door there is no friction between the door and the frame at the top or sides. However, the construction at the bottom of the door is different.

At the bottom the door moves relative to a threshold or, in its absence, to the floor. At this location friction is present in any swinging door and it is for that reason that a definite clearance must be provided between the bottom surface of the door and the upper surface of the threshold or the floor. From time to time, when the door swells or its hinges sag, it rubs on the threshold or floor in opening and closing and, in order to prevent this action, it is necessary to remove the door and trim off a portion of its bottom. For this reason it is not feasible to treat the bottom surface of a door with oil, stain, varnish, or the like, to protect it from moisture which can be done for the other door surfaces.

When rain, snow, sleet, or hail beat against the door, the resulting moisture runs down the outer surface thereof and some of it tends to flow over the threshold to the inside of the building. This causes the door to swell and stick in addition to causing an accumulation of water inside the door. Snow tracked or blown between the threshold or floor and the bottom of the door melts and acts in much the same way. Because of the clearance which must be left between the bottom of the door and the threshold or floor, dust, dirt, and cold air may enter the building at this point. Usually there is a draft between the bottom of the door and the threshold or floor even though weather-stripping of the prior art is employed therebetween.

2

Accordingly, among the objects of my invention are: To deflect rain, snow, etc., away from the bottom of a door; to provide a weather tight seal for the bottom of a door; to have a minimum of friction between the bottom of the door and the adjacent surface of the threshold or floor when the door is swung to and from the closed position while maintaining a weather tight seal; to employ a sheet of readily deformable material to make the seal; to fasten the sheet and shape the same in such manner that the major portion of it rolls along the surface of the threshold or floor during the opening or closing movement of the door; and to contain the sheet in such manner that it is not subject to sharp bending likely to cause the same to rupture.

Other objects of my invention will, in part, be obvious and in part appear hereinafter.

My invention is disclosed in the embodiments thereof shown in the accompanying drawings and it comprises the features of construction, combination of elements and arrangement of parts which will be exemplified in the constructions hereinafter set forth and the scope of the application of which will be indicated in the appended claims.

For a more complete understanding of the nature and scope of my invention, reference can be had to the following detailed description, taken together with the accompanying drawings, in which:

Figure 1 is a view, in front elevation, of the lower portion of a conventional door and door frame with my invention applied to the door bottom;

Figure 2 is a detail sectional view of a portion of the door bottom and one embodiment of my improved sealing means therefor;

Figure 3 is a view, similar to Figure 2, and illustrating how the sheet of rubber-like sealing material is deformed in engagement with the threshold when the door is closed;

Figure 4 is a detail sectional view taken along the line 4—4 of Figure 2;

Figure 5 is a perspective view of the parts making up the sealing means illustrated in the preceding figures, the parts being shown in disassembled relation;

Figure 6 is a detail sectional view of another embodiment of my invention; and

Figure 7 is a view, similar to Figure 6, and illustrating how the sheet of rubber-like material is deformed when in contact with the threshold with the door in the closed position.

Referring now particularly to Figure 1 of the

drawings it will be noted that the reference character 10 designates a conventional door which may be formed of wood. The door 10 is arranged to be swung by hinges (not shown) in a door frame which includes a pair of upright door frame members 11. The door 10 is arranged to swing relative to a threshold 12. However, it will be understood that the threshold 12 often is omitted and provision is made for the door 10 to swing only over the floor, the floor usually sloping away from the door so as to provide a threshold effect.

In Figures 2 and 3 of the drawings there is illustrated, generally, at 13 one embodiment of my improved door sealing means. It includes a channel, shown generally at 14, which may be formed of corrosion resistant material, such as stainless steel or aluminum. The channel 14 has a central flat portion 15 which is arranged, as shown, to engage the bottom surface 16 of the door 10. It may be held in place therealong by suitable means such as screws 17. It will be obvious that various thicknesses of door 10 can be employed with a given channel 14. Preferably the width of the central portion 15 exceeds the thickness of the door 10.

The channel 14 is provided with downturned and outflared sides 18. The outer surfaces thereof serve to deflect moisture which may fall on one or the other of the sides of the door 10 away from the bottom surface 16 thereof. These sides also perform additional functions which will be described hereinafter.

The outer edges 19 of the sides 18 are turned inwardly so as to form grooves 20 therealong as shown more clearly in Figure 5. These grooves 20 are provided for receiving edges 23 of strips 24 of stainless steel, aluminum, or the like, which have one portion 25 that extends entirely along the inner surface of the sides 18 as shown in Figures 2 and 3. Another portion 26 of each of the strips 24 extends along the underside of the central portion 15 of the channel 14 and is parallel thereto and to the bottom 16 of the door 10. The inner edges 27 of these portions 26 of the strips 24 are turned inwardly so as to provide grooves 28. The grooves 28 are provided for receiving the inturned edges 29 of a sheet 30 of relatively thin rubber-like material. The edges 27 are deformed onto the edges 29 of the sheet 30 so as to grip the same between them and the portions 26 of the strips 24.

As illustrated in Figures 2 and 3 the edges 29 of the sheet 30 are held parallel to the bottom surface 16 of the door 10. These limited portions or edges 29 of the sheet 30 are gripped inwardly of the outwardly bowed sides 31 of the sheet 30 so that the intermediate portion 32 thereof, which is arched downwardly to engage the upper surface of the threshold 12 or a floor, can roll with respect thereto when the door 10 is swung to or from the closed position.

It will be understood that the sheet 30 of relatively thin rubber-like material, preferably a good grade of gasket material, is assembled with the strips 24 as a unitary construction which is illustrated in Figure 5. After the channel 14 has been secured in place along the bottom surface 16 of the door 10 by the screws 17, the strips 24 attached to the sheet 30 can be slid into place with the edges 23 being positioned in the grooves 20 of the channel 14. If it is desired to lock the strips 24 in the assembled position, cleats 33 may be employed. As shown in Figure 4 the cleats 33 extend transversely of the bottom or central portion 15 of the channel 14 and are held

in place by the screws 17. The cleats 33 are assembled with the channel 14 and they are sufficiently resilient so that the strips 24 can be slid therewith. The cleats 33 then frictionally grip the strips 24, as shown in Figure 3, and hold the same in position.

The shape of the intermediate portion 32 of the sheet 30 in the door closed position is illustrated in Figure 3. It will be noted that a substantial portion of it rests flat against the upper surface of the threshold 12. Because of the fact that the sheet 30 is readily deformable, it shapes itself to any irregularities which may be present in the upper surface of the threshold 12 so as to provide a weather tight seal therebetween.

Now when the door 10 is swung to the open position, for example moved in the direction indicated by the arrow 34 in Figure 3, the intermediate portion 32 has rolling rather than sliding engagement with the upper surface of the threshold 12. The reason for this is that the sheet 30 is fastened only along its inturned edges 29 and otherwise is unrestrained except as it is confined by the sides 18 of the channel 14. Thus, as the door 10 swings in the direction indicated by the arrow 34, the left hand side 31 of the sheet 30 engages the left hand outer edge 19 of the left hand side 18 of the channel 14 while the left hand side of the intermediate portion 32 rolls out from underneath the lowermost edge of the side 18. This action is permitted since the right hand side 31 of the sheet 30 is free to move away from the inner surface of the right hand strip 24. The construction and proportioning of parts are such that the sheet 30 of relatively thin rubber-like material is not subjected to any sharp bending which, after repeated operations, might cause the same to crack and rupture. It will be understood that, when the door 10 is swung in the opposite direction, the right hand side of the intermediate portion 32 of the sheet 30 rolls out from underneath the lowermost edge of the right hand side 18 of the channel 14 while the left hand side 31 moves away from or disengages the left hand strip 24.

In Figures 6 and 7 of the drawings another embodiment of the invention is illustrated. As there shown, a pair of strips 40 of stainless steel, aluminum, or the like, is provided for location along the bottom of the door 10. Each strip has an extension 41 that extends upwardly along the opposite surfaces of the bottom of the door 10. Suitable means, such as screws 41', may be employed to hold the extensions 41 in place along the bottom of the door 10. Each extension 41 is formed integrally with an outer layer 42 of a double layer portion 43 which extends outwardly and downwardly for the purpose of deflecting moisture and controlling the position of the sheet 30 of relatively thin rubber-like material in the manner described hereinbefore. An inner layer 44 of each of the double layer portions 43 has an inwardly extending flat portion 45 which is arranged to engage the bottom surface 16 of the door 10 as shown. Each portion 45 has an inturned edge 46 which is deformed onto the inturned edge of the sheet 30 associated therewith for frictionally gripping the same.

The functioning of the sealing means illustrated in Figures 6 and 7 is essentially the same as described hereinbefore for the sealing means illustrated in the preceding figures.

It will be apparent that the sealing means illustrated in Figures 6 and 7 is adaptable, within limits, to different thicknesses of the door 10

while maintaining the same relative position with respect thereto insofar as the strips 40 are concerned.

Since certain further changes can be made in the foregoing constructions and different embodiments of the invention can be made without departing from the spirit and scope thereof, it is intended that all matter shown in the accompanying drawings and described hereinbefore shall be interpreted as illustrative and not in a limiting sense.

I claim as my invention:

1. Sealing means for the bottom of a door comprising, in combination, a sheet of rubber-like material for extending along the bottom of the door with its edges turned inwardly and its intermediate portion arched downwardly to engage a threshold or floor with a rolling action, means for securing the edges of said sheet to said door, and outwardly and downwardly flared flange means for extending along the inner and outer edges of said door and overlying and simultaneously engaging both of the juxtaposed portions of said intermediate portion of said sheet so that the inside of said flange means on the side away from the direction in which the door is moved from one position to another is engaged while the inside of the other flange means is disengaged.

2. Sealing means for the bottom of a door comprising, in combination, outwardly and downwardly flared flange means for extending along the bottom edges of the door, a sheet of rubber-like material for extending along the bottom of the door with its edges turned inwardly and its intermediate portion arched downward to engage a threshold or floor and arranged to be deformed on contact therewith and to engage said flange means on the side away from the direction in which the door is moved from one position to another and to disengage the other flange means, and turned back edge means forming a part of said flange means frictionally gripping said inturned edges of said sheet of rubber-like material.

3. Sealing means for the bottom of a door comprising, in combination, a sheet of rubber-like material for extending along the bottom of the door with its edges turned inwardly and its intermediate portion arched downwardly to engage a threshold or floor with a rolling action, fastening means for securing a limited portion of said sheet along each edge substantially parallel to the bottom surface of said door and inwardly from the edges thereof, and outwardly and downwardly flared flange means for extending along the inner and outer edges of said door and overlying and simultaneously engaging both of the juxtaposed portions of said intermediate portion of said sheet so that the inside of said flange means on the side away from the direction in which the door is moved from one position to another is engaged while the inside of the other flange means is disengaged.

4. Sealing means for the bottom of a door comprising, in combination, channel means for extending along the bottom of the door with the sides thereof flared outwardly and downwardly so that the outsides thereof can deflect rain and snow from the door, a sheet of rubber-like material extending lengthwise of said channel means with its longitudinal edges turned inwardly and its intermediate portion arched downwardly to engage a threshold or floor and its side between said edges and said intermediate portion engaging the respective insides of said channel

means, and fastening means securing said edges of said sheet in position along said channel means, said arched portion being deformed on contact with a floor or threshold and engageable with the inside of said channel away from the direction in which the door is moved from one position to another and disengageable with the other inside of said channel.

5. Sealing means for the bottom of a door comprising, in combination, channel means for extending along the bottom of the door with the sides thereof flared outwardly and downwardly, a sheet of rubber-like material extending lengthwise of said channel means with its longitudinal edges turned inwardly and its intermediate portion arched downwardly to engage a threshold or floor and its side between said edges and said intermediate portion engaging the respective insides of said channel means, and fastening means securing said edges of said sheet in position along said channel means with a limited portion of said sheet along each edge substantially parallel to the bottom surface of the door, said arched portion being deformed on contact with a floor or threshold and engageable with the side of said channel away from the direction in which the door is moved from one position to another and disengageable with the other side of said channel.

6. Sealing means for the bottom of a door comprising, in combination, a channel for extending along the bottom of the door with the sides thereof flared outwardly and downwardly and the edges thereof turned inwardly to form grooves, a sheet of rubber-like material extending lengthwise of said channel with its longitudinal edges turned inwardly and its intermediate portion arched downwardly to engage a threshold or floor, and fastening means securing said edges of said sheet in position along said channel means and slidably in said grooves whereby said sheet and fastening means are separable as a unit from said channel.

7. Sealing means for the bottom of a door comprising, in combination, a channel for extending along the bottom of the door with the sides thereof flared outwardly and downwardly, and the edges thereof turned inwardly to form grooves, a sheet of rubber-like material extending lengthwise of said channel with its longitudinal edges turned inwardly and its intermediate portion arched downwardly to engage a threshold or floor, fastening means securing said edges of said sheet in position along said channel means and slidably in said grooves whereby said sheet and fastening means are separable as a unit from said channel, and cleat means extending transversely of the bottom of said channel and cooperating with said fastening means to hold the same in place.

8. Sealing means for the bottom of a door comprising, in combination, a channel for extending along the bottom of the door with the sides thereof flared outwardly and downwardly and their edges turned inwardly to form grooves, a sheet of rubber-like material extending lengthwise of said channel with its longitudinal edges turned inwardly and its intermediate portion arched downwardly to engage a threshold or floor, and a fastening strip for each edge of said sheet having a portion extending along the inner surface of the adjacent side of said channel with the edge thereof extending into the groove therealong and another portion extending along the bottom of said channel with its edge turned

inwardly to grip frictionally the adjacent edge of said sheet.

9. Sealing means for the bottom of a door comprising, in combination, a channel for extending along the bottom of the door with the sides thereof flared outwardly and downwardly and their edges turned inwardly to form grooves, a sheet of rubber-like material extending lengthwise of said channel with its longitudinal edges turned inwardly and its intermediate portion arched downwardly to engage a threshold or floor, a fastening strip for each edge of said sheet having a portion extending along the inner surface of the adjacent side of said channel with the edge thereof extending into the groove therealong and another portion extending along the bottom of said channel with its edge turned inwardly to grip frictionally the adjacent edge of said sheet, and cleat means extending transversely of the bottom of said channel and arranged to bear against said inturned edges of said strips to hold the same and said sheet in place.

10. Sealing means for the bottom of a door comprising, in combination, a pair of strips for extending along the bottom edges of the door each having a downwardly and outwardly extending portion and another portion for extending along and engaging the bottom surface of the door, and a sheet of rubber-like material for extending along the bottom of the door with its edges turned inwardly and secured to said other portions of said strips and its intermediate portion arched downwardly to engage a threshold or floor and arranged to be deformed on contact therewith and to engage the downwardly and outwardly extending portion of the strip on the side away from the direction in which the door is moved from one position to another and to disengage the corresponding portion of the other strip.

11. Sealing means for the bottom of a door comprising, in combination, a pair of strips for extending along the edges of the door bottom each having a downwardly and outwardly extending portion and another portion for extending along and engaging the bottom surface of the door with its edge turned back to form a groove, and a sheet of rubber-like material for extending along the bottom of the door with its edges turned inwardly and frictionally gripped in said grooves and its intermediate portion arched downwardly to engage a threshold or floor.

12. Sealing means for the bottom of a door comprising, in combination, a pair of strips for extending along the edges of the door bottom each having a downwardly and outwardly extending portion and another portion for extending along and engaging the bottom surface of the door with its edge turned back to form a groove, each of

said strips having an extension for projecting upwardly along the adjacent vertical surface of the door to facilitate fastening the same thereto, and a sheet of rubber-like material for extending along the bottom of the door with its edges turned inwardly and frictionally gripped in said grooves and its intermediate portion arched downwardly to engage a threshold or floor.

13. Sealing means for the bottom of a door comprising, in combination, a pair of strips for extending along the edges of the door bottom each having a downwardly and outwardly extending portion and another portion for extending along and engaging the bottom surface of the door with its edge turned back to form a groove, each of said strips having an extension for projecting upwardly from its downwardly and outwardly extending portion along the adjacent vertical surface of the door to provide for fastening the same thereto, and a sheet of rubber-like material for extending along the bottom of the door with its edges turned inwardly and frictionally gripped in said grooves and its intermediate portion arched downwardly to engage a threshold or floor.

14. Sealing means for the bottom of a door comprising, in combination, a pair of strips for extending along the edges of the door bottom each having a double layer downwardly and outwardly extending portion with one layer for projecting upwardly along the adjacent vertical surface of the door to facilitate fastening the same thereto and the other layer for extending along and engaging the bottom surface of the door with its edge turned back to form a groove, and a sheet of rubber-like material for extending along the bottom of the door with its edges turned inwardly and frictionally gripped in said grooves and its intermediate portion arched downwardly to engage a threshold or floor.

RALPH E. UPHOFF.
